UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PAPER FOLDING CARTON AND THE LIKE.

Application filed November 13, 1924. Serial No. 749,797.

To all whom it may concern:

Be it known that I, SAMUEL BERGSTEIN, a citizen of the United States, residing at Middletown, in the county of Butler and 5 State of Ohio, have invented certain new and useful Improvements in Paper Folding Cartons and the like, of which the following is a specification, reference being had therein to the accompanying drawings.

10 This invention relates to improvements in paper boxes, having particular reference to containers for breakable products, as eggs.

The object attained in the invention is 15 an improved box suitable to contain eggs in quantities, preferably a dozen to a box, and which will be more effective to prevent breakage of the eggs in shipping and handling incident to the distribution thereof.

A further object attained in the invention 20 is a box made from a one-piece blank, adapted to be made by automatic or semi-automatic machinery,—a box suitable for nesting one unit in another, as delivered from the box forming machine, to reduce 25 the bulk of quantity lots for shipping and storing, and easy to set up to receive the product,—also adapted to be easily and securely closed to insure full protection of the contents in shipping and handling.

30 To this end my improved box is provided with means to support each egg fully suspended and entirely out of engagement one egg with another, the means for supporting the eggs being yieldable and adapted to provide a cushioning element between the eggs, 35 and thus to minimize shocks to the contents of the carton received in handling.

A further feature of the invention consists 40 in the shape of the paper box,—the lid of the box being so associated with the body thereof to effect compression of the sides and of a spacing partition or diaphragm intermediate the sides whereby each unit of the contents is yieldingly held in place 45 thus acting to prevent free lateral movement thereof and all possibility of one unit contacting with another and breakage resulting under normal conditions of handling.

50 These features and the details of construction of the improved paper box comprised in the improvements are illustrated in the accompanying drawings, described in detail

in the following specification and defined in their coordinated relation one part with another in the appended claims. 55

In the drawings:

Fig. 1 is a diagram illustrating the manner of cutting the box blanks to minimize waste of material;

Fig. 2 is a view illustrating the manner of nesting the boxes for handling in bulk;

Fig. 3 is view of the box open with the diaphragm folded ready to be adjusted in the box;

Fig. 4 is a perspective view of the box 65 open ready for use;

Fig. 5 is a cross-sectional view of the box;

Figs. 6 and 7 are side and end views respectively of the box closed;

As shown in Fig. 1, the box blank consists 70 of an integral piece adapted to be cut and scored by a single operation of a cutting and scoring press,—the blank consisting of a bottom portion 1, side portions 2—3, lid portions 4—5, end portions 6—7, diaphragm portions 75 8—9—10, side portion 2 being provided with a tongue 11 and lid portion 5 with slots 12 adapted to coact one with the other for securely closing the carton, parts 8 of the diaphragm with partially severed portions 13—14, and parts 9 with partially severed portions 15, which coact with parts 8 and 9 to support the eggs fully suspended and effectively spaced one from another as the box is filled, closed and packed for quantity 85 shipments.

The position of the eggs in the paper box is illustrated in Fig. 5. As here shown, it will be seen that the diaphragm as folded provides opposite triangular-shaped spaces 90 16—17 each flanked on one side with one of the parts 8 and on the opposite side with one of the parts 9, part 10 being directed downward parallel and in contact with side 95 3 of the box thus serving as a support for the free end of the diaphragm and also to strengthen the back side of the box,—part 5 of the lid acting in like manner to strengthen the front side.

It will be observed in Figs. 5 and 6 that 100 the sides of the box are tapered, the top of the box being substantially wider than the bottom; also that the incisions severing portions 13 and 14 one from another are at an

angle, this being for the purpose of adapting the angular edges of parts 13, as the parts are pressed outward toward the sides of the box, to be in full contact with the adjacent 5 tapered sides of the box, as the eggs are positioned between opposite parts 13—15, parts 14 being between the eggs and the sides of the box, and transversely opposite parts 15—15 being pressed toward the center of 10 the box from opposite sides into contact one with another.

It will be observed that the eggs are thus supported suspended above the bottom of the paper box and against lateral displacement 15 by the yieldable elements 13—15 which engage the eggs at four points, parts 14 acting as an added buffer between the eggs and the sides of the box.

The lid portion 4 is somewhat narrower 20 than the open top of the box, which has the effect upon closing the box of drawing the sides inward to some extent and of compressing the diaphragm to a like extent which tends to increase the pressure exerted on the 25 eggs supported between the retaining elements 13—15,—this action on the contents of the box being further increased by downward pressure on the intermediate portion 18 of the diaphragm which is substantially 30 higher than the body of the box and is thus brought into contact with the lid as the same is closed,—the upward projection of the part also serving to support the lid raised sufficiently to provide ventilation of the interior 35 of the box.

The lid is interlocked with the body of the box in a very simple but effective manner by means of the tongue 11 which is adapted to have its opposite, laterally projected portions 11^a inserted in slots 12 of lid portion 5 and thus to hold the lid securely engaged with side portion 2, a depending lip 11^b severed from part 11 being adapted to be pressed inward to enable ready engagement

of part 11 with the fingers to insert the tongue in slots 12.

No novelty is claimed with respect to the ends of the carton comprising parts 6 and 7, the same being folded and fastened one to the other, glued preferably, in the usual manner.

Having described my invention, I claim:

1. A paper box comprising a member formed integrally with a side of the box and adapted to be folded within the box to form a plurality of inclined walls therein with open spaces between the walls, the free end of said member being disposed adjacent the opposite side of the box substantially parallel thereto, partially severed portions arranged in each of said walls one opposite another transversely of said spaces and adapted to support a unit of the contents of the box yielding therebetween, an intermediate wall or said member being higher than the sides of the box whereby upon closing of the box said higher wall is compressed by another part of the box moved into relation therewith and added pressure is exerted yielding on the separately supported units of the contents of the box.

2. A paper box comprising upwardly and outwardly inclined sides, a member formed integrally with a side and adapted to be folded within the box to form a plurality of inclined walls therein with open spaces between the walls, yieldable elements in said walls arranged oppositely one of another transversely of said spaces and adapted to support a unit of the contents of the box therebetween, a lid for the box substantially narrower than the open top of the box and adapted when closed to compress the sides and said inner walls of the box and thereby to effect added pressure on the contents of the box through said yieldable element.

In testimony whereof, I affix my signature.

SAMUEL BERGSTEIN.
